A. V. ROWE,
ATTACHMENT FOR HOG OILERS,
APPLICATION FILED AUG. 20, 1915.

1,174,523.

Patented Mar. 7, 1916.

WITNESS:
John G. Ballentine.

INVENTOR:
Alvin V. Rowe,
By H. M. Richards,
Atty.

UNITED STATES PATENT OFFICE.

ALVIN V. ROWE, OF GALESBURG, ILLINOIS.

ATTACHMENT FOR HOG-OILERS.

1,174,523.

Specification of Letters Patent. Patented Mar. 7, 1916.

Application filed August 20, 1915. Serial No. 46,465.

To all whom it may concern:

Be it known that I, ALVIN V. ROWE, a citizen of the United States, and a resident of Galesburg, in the county of Knox and State of Illinois, have invented a new and useful Attachment for Hog-Oilers, of which the following is a specification.

My present invention relates to devices attachable to hog-oilers or rubbing-posts of practically any construction, which devices are adapted to apply oil or the like to and over the bellies and lower parts of an animal rubbing thereon.

The invention consists, substantially, in the improvements herein disclosed.

The principal object of the invention is to generally improve the construction, to increase the utility and efficiency, and to decrease the expense attendant upon the use of devices of this character.

More specifically stated, the improvements are directed toward the provision of a novel oil-cup disk; toward the cut-off for furnishing oil thereto; toward regulating the amount of oil furnished; toward the provision of co-acting portions of the oil-cup disk and oil-releasing push-button, whereby the latter cannot be displaced by movements of the animal; toward the provision of a dust, dirt and grit-collecting chamber; and toward the provision of minor features of utility, some of which will be obvious and others specifically pointed out.

A preferred embodiment of my improvements is illustrated in the accompanying drawing, wherein:

Figure 1 is a side elevation, showing my improvements as attached to a hog-oiler or rubbing-post of well known construction; Fig. 2, a top plan of the oil-cup disk; Fig. 3, a top plan of the valve case; Fig. 4, an elevation of my improvements, assembled; Fig. 5, an elevation of the valve-case; and Fig. 6, a vertical central section, taken in the plane of the line 6—6 in Fig. 2. Figs. 2 to 6 inclusive are greatly enlarged with reference to Fig. 1.

Referring to the elements and, where necessary, to parts thereof, each by a distinguishing reference character, uniformly employed, 2 designates a platform upon which is secured a hog-oiler comprising a base 3, supporting post 4, tank 5 having a bottom 6, and rubbing-plates 7, either or all of which may be of any suitable and preferred construction, it being understood that the at-

tachments later herein described and which constitute my improvements, may be successfully adapted to practically any device of like or similar nature.

The tank-bottom 6 is provided with a threaded aperture into which is threaded one end of a supply-pipe 9 the other end of which is threaded into an aperture 13 in a casing 10 having feet 11 resting on the platform 2 or other support.

12—12 designate screws for securing said feet to the platform.

The casing 10 is provided near its upper edge with radially extended ears 14 provided each with an aperture 15. Seated on the top or upper edge of the casing 10 (which is open at its upper end) is a gasket 16 upon which rests the flange 17 of a valve-case 18.

19 designates an annular, axially arranged projection which together with the bottom 20 of the case 18 provides a dirt, dust and grit collecting receptacle. The central portion 25 of said case extends downward and its lower end is provided with a smooth bore 80 aperture through which freely passes a screw-bolt valve-stem 21 having a threaded foot which is engaged by a valve-closing and charge-regulating nut 22.

23 designates an expansion spring embracing the valve-stem, and 24 indicates a gasket carried on said stem and supported by said nut.

27 designates a lip adapted to prevent the nut 22 from turning when the valve-stem 90 is being adjusted therein.

The oil-cup disk is designated by 28 and has a hub 29 provided with an axially arranged groove 30. Its face is provided with a plurality of arcuate cups 31 the sides of which are afforded one by an annular flange 32' and an arcuate embossment 32 and the sides of the others by said embossments, the ends of the cups being afforded by partitions 33. The lower end of the hub has a projection 34 through which the groove 30 is continued. The disk is provided with apertures corresponding or registering with those in the ears 14 in the casing 10, and through each registering pair of these is passed a bolt 35 engaged by a nut 36.

37 indicates a gasket between the valve-case projection 19 and a similar one on the lower face of the disk 28, and when the bolts 35 are drawn taut forms an oil-seal 110 between said parts.

The stem 38 of a mushroom-shaped valve-

actuating push-button 39 is seated loosely in the opening in the hub 29, its top covering said opening. At the lower end of said stem is a horizontally arranged tongue 40. To 5 position the button 39 said tongue is so placed that it will enter the channel 30, thus permitting the stem to pass through the hub and the tongue through the projection 34, below which it cannot pass until the tip of 10 the stem has been forced down onto the head of the valve-stem 21 to depress it, whereupon the button may be turned on its axis until the tongue has passed the projection 34. The spring 23 will then expand and 15 force the button upward, and it will be evident that no movement of or by an animal can displace it whereby to render the device inoperative.

The operation is as follows: The oil will 20 flow from the tank 5 through the pipe 9 and into the casing 10 until the latter is filled. An animal in attempting to scratch any of its lower portions will bear upon the button 39, thus forcing its lower end down onto the 25 head of the valve-stem 21, overcoming the resistance of the spring 23, depressing the nut 22 and gasket 24 and opening the valve. The oil will then flow into the chamber between the valve-case and oil-cup disk, out 30 through the opening in the hub 29 and thence into the several oil-cups in said disk, available and in position to be distributed over the belly, neck and jowl of the animal. The 35 outer embossment is in a lower horizontal plane than the next adjacent one, and the latter in a lower plane than the most central one; therefore the oil will flow from the inner to the intermediate and thence to the outer oil-cups and will be restrained from 40 flowing off the disk by reason of the rim or annular flange 32' which lies preferably in the same horizontal plane as does the intermediate embossment 32.

Each rapid complete reciprocation of the 45 button will displace and release a measured quantity of oil, and an incomplete but rapid reciprocation thereof will release a less quantity. The amount to be released at each quickly completed actuation may be regulated by adjustments of the valve-stem in and relatively to the nut, and this operation further serves to regulate the tension of the 50 spring, for actuation by larger or smaller hogs.

Should the device become tilted from the 55 perpendicular there would be but an inconsequential loss of oil, for the partitions 33 would retain that contained in the uppermost oil-cups. Also, these partitions aid the 60 portions 32, 32' in applying the oil to the body of the animal.

Although the exact structure of the preferred embodiment of the invention has hereinbefore been described, I do not intend, 65 by describing it in detail, to be understood

as limiting myself in any way or manner thereto, the scope of the invention being pointed out in the claims hereto appended.

Having thus described the nature of the invention I claim as new and desire to secure 70 by Letters Patent the following, namely:

1. In a device of the nature described, a casing, an oil-cup disk having a central opening, a valve-case supported on said casing, a valve-stem therein, a push-button having a 75 stem loosely mounted in said opening and adapted to actuate said valve-stem, said disk and stem having co-acting portions whereby said button cannot be displaced by an animal, and means for forcing liquid into said 80 casing and onto said disk.

2. In a device of the nature described, a casing, an oil-cup disk having a central opening and an axially arranged channel communicating therewith, a valve communicating 85 with said casing and opening, means for securing said elements together, valve-actuating means mounted in said opening and having a tongue adapted to be passed down said channel and to be turned to a position 90 out of registration therewith after placement, and means for forcing liquid into said casing and onto said disk.

3. In a device of the nature described, a casing, an oil-cup disk having a hub provided with a downward projection, said hub and projection provided with a continuous channel, a valve communicating with said casing and hub, means for securing said elements together, valve-actuating means 95 mounted in said hub and having a tongue adapted to be passed through said channel and to be turned to a position out of registration therewith after placement, and means for forcing liquid through said casing and onto said disk.

4. In a device of the nature described, a casing, an oil-cup disk having a hub provided with a downward projection, said hub and projection provided with a continuous 110 channel, a valve communicating with said casing and hub, means for securing said elements together, valve-actuating means mounted in said hub and having a tongue adapted to be passed through said channel and to be turned to a position out of registration therewith after placement, yielding 115 means for holding a member of said valve against said valve-actuating means, and means for forcing liquid through said casing and onto said disk.

5. In a device of the nature described, a casing, an oil-cup disk having an opening communicating therewith, a valve-case having an opening in its bottom and a depending projection at one of its lower edges, a screw-bolt valve-stem arranged in said case and passed through said opening therein, a nut on the stem, prevented from rotation by said projection, valve-stem-actuating 125 130

means seated loosely in the opening in said disk and resting on said valve-stem, and means for forcing liquid through said casing and onto said disk.

5 6. In a device of the nature described, a casing, an oil-cup disk having an opening communicating therewith, a valve-case having an opening in its bottom and a depending projection at one of its lower edges, a
10 screw-bolt valve-stem arranged in said case and passed through said opening therein, a nut on the stem, prevented from rotation by said projection, valve-stem actuating means seated loosely in the opening in said disk
15 and resting on said valve-stem, a spring adapted to hold said valve-stem and thereby said valve-stem-actuating means in positions to be operated by an animal bearing upon the latter, and means for forcing
20 liquid through said casing and onto said disk.

7. In a device of the character described, an oil-cup disk having a hub provided with an axially arranged channel, valve-actuating means provided with a projection adapted to be passed through said channel and to be turned, after such passage, out of registration therewith, a valve-structure actuated by the valve-actuating means and communicating with the opening in said hub, and a source of oil-supply communicating with said valve structure, said source adapted to force liquid past said valve structure, through the opening in the hub, and onto
35 the disk.

8. The combination with a tank, of a casing, a pipe communicating with both thereof, a valve structure communicating with the casing, an oil-cup disk having a central opening communicating with said valve structure, animal-actuable means for opening the valve structure, a gasket between the disk and valve structure, and a gasket between the casing and valve structure, said
40 tank adapted to force liquid through said casing, pipe, valve structure and central opening, onto said disk.

9. A device of the nature described comprising a base having ears each of which
50 has an aperture, an oil-cup disk having a central opening and having apertures reg-

istering with those in said ears, a valve structure supported by said casing and supporting said disk, bolts passed one through each registering pair of eyes in said ears
55 and disk, nuts, one on each bolt, means for operating the valve structure, and means for supplying said disk with liquid, through said casing, valve structure and central opening.

10. An oil-cup disk having a central opening and a plurality of arcuate embossments on its upper face, said face provided also with radially arranged partitions cutting the depressions between said embossments, and
65 means, communicating with said opening, for supplying liquid to said face.

11. An oil-cup disk having a central opening and having on its upper face a plurality of embossments arranged in arcs of
70 circles, there being partitions cutting the depressions between said embossments, and means, communicating with said opening, for supplying liquid to said upper face.

12. An oil-cup disk having a central opening and having a plurality of arcuate embossments arranged in gradually descending planes, and means for supplying liquid, through said opening, to the upper face of
75 said disk.

13. An oil-cup disk having a central opening and having a plurality of arcuate embossments, said disk provided with a peripherally arranged oil-retaining rim, and means for supplying liquid, through said
80 opening, to the upper face of said disk.

14. An oil-cup disk having a centrally arranged hub and an axially arranged projection therefrom, said portions provided with a continuous channel running longitudinally
90 of the hub, valve-operating means rotatably mounted in said hub and having a projection adapted to be slid in said channel, valve structure operable by said valve-operating means, a casing in which said valve structure is mounted, and means for forcing liquid through said casing, valve structure and hub, onto said disk.

In testimony whereof I hereto subscribe my name this 14th day of August, 1915, at
100 Galesburg, Illinois.

ALVIN V. ROWE.
